Primary Examiner — George D. Kirschbaum

Assistant Examiner — Maria J. Edwards

(57) CLAIM

The ornamental design for a heated glove, as shown and described.

DESCRIPTION

FIG. 1 is a front perspective view of a heated glove, showing my new design;

FIG. 2 is a rear elevation view thereof;

FIG. 3 is a right side elevation view thereof;

FIG. 4 is a left side elevation view thereof;

FIG. 5 is a bottom plan view thereof;

FIG. 6 is a top plan view thereof; and,

FIG. 7 is a front perspective view thereof.

The broken lines in the figures depict portions of the heated glove that forms no part of the claimed design.

1 Claim, 7 Drawing Sheets
